BOTTLING MACHINE

Richard T. Allen, Kansas City, Mo., assignor to
V. Jack Vincent, Lawrence, Kans.

Application August 30, 1944, Serial No. 551,816

5 Claims. (Cl. 226—116)

1

This invention relates to carton filling equipment and more specifically, to loading apparatus for bottles where a liquid is to be introduced into a number of containers simultaneously, and the flow terminated at a particular given time during the filling operation.

One of the important aims of the instant invention is to provide a bottling machine capable of introducing liquid into several bottles or the like, and manually stopping the flow of the liquid when the level in the bottles reaches a predetermined point.

This invention has for one of its important aims to provide a machine of the aforementioned character, with parts for establishing a back pressure or suction in the feed pipes, whereby accuracy of "cut-off" is insured and the operator may positively check the flow of liquid without danger of a continuation thereof.

Other objects of the invention will appear during the course of the following specification, referring to the accompanying drawing, wherein:

Fig. 1 is a side elevational view of a bottling machine made in accordance with the present invention and having parts thereof in section and broken away for clearness; and

Fig. 2 is a top plan view of the bottling machine.

Small producers of liquid products marketed in bottles or containers, have difficulty in expeditiously filling the containers because of their inability to obtain bottling apparatus without the expenditure of excessive sums of money. It has therefore, been the custom for such small producers to fill the bottles one at a time and it is the aim of this invention to provide a bottling machine that is inexpensive, easy to handle, and capable of serving a relatively large number of containers.

The illustrated embodiment of the invention shown in the drawing comprises a reservoir 10 having a removable cover 12, axially perforated as at 14 to receive a conduit 16 extending to a source of supply, not here shown. The liquid to be bottled may be in an elevated tank where the action of gravity serves as a means for introducing the liquid into reservoir 10, or the liquid may be pumped through conduit 16—all to suit conditions.

Conduit 16 is screw threaded into perforation 14 and extends approximately six inches below cover 12 as clearly shown in Fig. 1.

Cover 12 has a number of internally threaded openings 18 therein to receive one end of a pipe

2

20 that is threaded or otherwise fastened in place with its end just below the under surface of cover 12. Pipe 20 extends laterally from reservoir 10 to a point above the receptacle 22 into which the liquid is to be emptied.

The outer or free end of pipe 20 is reduced in diameter and assumes the U-shaped form illustrated in Fig. 1. This U-shaped section is generally designated by the numeral 24 and the outer leg terminates in a curled lip 26 disposed to deflect the liquid against one side of container 22.

A pin 28 extends into one of the legs of section 24 to selectively restrict the passage through which the liquid must flow. Suitable lock nuts 30 are on pin 28 to maintain the same in a set condition.

Conduit 16 has a quick acting gate valve 32 therein and this valve is operably joined by crank 34 to a reciprocating rod 36 having handle 38 at one end thereof. A pump 40 joined to conduit 16 by connection 42 has its piston rod 44 connected to rod 36 by head 46. A piston 48 in pump 40 serves the usual function so far as the pump is concerned, and will be more fully explained herein.

A drain cock 50 is in communication with connection 42. A branch pipe 52 extends laterally from conduit 16 and thence downwardly to terminate at an open end below the top of reservoir 10 and above the end of conduit 16 therein. This branch pipe 52 has a valve 54 interposed in its length for use as hereinafter described.

In operation, the bottling machine is connected to a source of liquid by conduit 16 and the several containers 22 placed below U-shaped sections 24—all as illustrated in the drawing. Valves 50 and 54 are closed and valve 32 is initially closed until containers 22 are in place. A pull on handle 38 will open valve 32 and move piston 48 of pump 40 to the innermost end of its path of travel. Thus, liquid will flow through conduit 16 into reservoir 10 and thence out through pipes 20 and into containers 22. When the level of the liquid in these containers reaches the desired point, handle 38 is manipulated to close valve 32. This manipulation simultaneously draws piston 48 out to the position shown in Fig. 1, to create a back pressure or suction in conduit 16 and reservoir 10. This suction will immediately relieve the pressure in reservoir 10 and preclude liquid from passing through the pipes 20 into containers 22. Valve 32 and crank 34 is so interengaged as to close valve 32 before piston 48 reaches the end of its path of travel or that place illustrated in Fig. 1. The

55 elevated position and reduced diameter of U-

shaped sections 24 will also insure a back flow because as soon as valve 32 is closed, the liquid in each pipe 20 will tend to return to reservoir 10 and thereby establish a suction in U-shaped sections 24. Thus, an accurate filling may occur.

Branch pipe 52 may empty into a container similar to those designated by the numeral 22 and may be employed if pump 40 is not in use. This branch pipe 52 will siphon liquid from reservoir 10 when the valve 54 is open to likewise establish a back pressure or suction in pipes 20.

In the operation of the machine where pump 40 is not used and branch pipe 52 is employed, valve 54 should be opened just before valve 32 is closed in order to establish a flow of liquid through branch pipe 52. This flow will continue when the supply is shut off by closing valve 32. The siphoning established will create the necessary suction and the flow of liquid through pipe 20 will immediately stop when valve 32 is closed.

The machine is capable of accurately filling small bottles down to ounce capacity, for example. When the equipment is so used, valve 32 is disconnected from rod 36 to be operated independently. Valve 17 is closed and valve 32 opened while pump 40 is at the end of the path of travel shown in dotted lines of Fig. 1. Then piston 48 of pump 40 is moved to the position shown in full lines of Fig. 1, where pump barrel 40 is filled. Valve 32 is then closed and valve 17 opened, whereupon piston 48 is returned to the first-mentioned position to force the liquid downwardly through conduit 16 and thence to the containers of relatively small capacity.

It is understood that bottling machines having appearances and physical characteristics different from those shown and described, may be made without departing from the spirit of the invention or scope of the appended claims.

Having thus described the invention, what is claimed as new and desired to be secured by Letters Patent is:

1. A bottling machine comprising a closed reservoir; a plurality of pipes extending from the reservoir to a point above the bottles being filled and in communication therewith at the top thereof; a conduit interconnecting a source of supply with the reservoir; a valve in the conduit to control the flow of liquid therethrough; and means joined to the valve for actuation thereby for creating a suction in said conduit and in the reservoir and the pipes through the conduit when the said valve is closed.

2. A bottling machine comprising a closed reservoir; a plurality of pipes extending from the

reservoir to a point above the bottles being filled and in communication therewith at the top thereof; a conduit interconnecting a source of supply with the reservoir; a valve in the conduit to control the flow of liquid therethrough; and means on each pipe for varying the size of the passage therethrough near the bottle being filled.

3. A bottling machine comprising a closed reservoir; a plurality of pipes extending from the reservoir to a point above the bottles being filled and in communication therewith at the top thereof; a conduit interconnecting a source of supply with the reservoir; a valve in the conduit to control the flow of liquid therethrough; and a curled lip on the outer end of each pipe for directing the liquid against the side of the bottle being filled.

4. A bottling machine comprising a closed reservoir; a plurality of pipes extending from the reservoir to a point above the bottles being filled and in communication therewith at the top thereof; a conduit interconnecting a source of supply with the reservoir; a valve in the conduit to control the flow of liquid therethrough; and means interposed in the conduit between the the valve and reservoir for creating a suction in the conduit and resultant suction in the reservoir and the pipes, said means being operably connected to the said valve for simultaneous operation therewith, said connection being formed to permit continued operation of said means after operation of the valve is ceased.

5. A bottling machine comprising a closed reservoir; a plurality of pipes extending from the reservoir to a point above the bottles being filled and in communication therewith at the top thereof; a conduit interconnecting a source of supply with the reservoir; a valve in the conduit to control the flow of liquid therethrough; and a pump for creating a suction in the reservoir and the pipes when the said valve is closed, each of said pipes terminating in inverted U-shaped sections of smaller bore than the remaining portion of pipes, said remaining portion of the pipes being lower than the U-shaped sections.
